SETTEE AND GLIDER

Charles Zachary Borochoff, Atlanta, Ga., assignor to Southern Wire & Iron Works, Atlanta, Ga., a partnership

Application October 1, 1948, Serial No. 52,370

1 Claim. (Cl. 155—112)

This invention has for its object to provide a novel construction of a chair or settee (dependent on the length of the seat and back sections) which may be either a glider or not and in which great resiliency of the seat is provided with ample rigidity and for this purpose consists of a novel arrangement of parts and method of assemblage as will be hereinafter described and claimed.

Referring now to the drawings, in which corresponding parts are indicated by corresponding marks of reference—

Figure 1 is a perspective view of a settee embodying this invention.

Figure 2 is the same construction when embodied in a glider.

Figure 3 is a fragmental vertical section from the front to the rear of the settee shown in Figure 1.

Figure 4 is a detail showing a step in the method of assemblage.

Figure 5 is a fragmental view on an enlarged scale of the method of fastening the front and rear of the seat strap and the bottom of the back straps.

Figure 6 is a detail showing the manner in which the hangers 11 are connected to the rest of the frame.

To form the frame there is provided two U-shaped ends 1 of tubular or channel construction, the lower halves of which form the bases 1a and the legs and the other half of which forms the arms 1b, the two ends being connected by the bar 2 bolted at its ends to the bases 1a, and by the front or seat bar 3. The seat bar has its ends bent at right angles and the bent portions are bolted to the vertical portions of the end members by bolts 4a. To permit vertical adjustment of the seat bar a series of holes 4b may be formed in the legs.

The seat is formed by the spaced resilient straps 5 fastened at their front end to the upper face of the front seat bar, their rear ends being inserted between the two rear seat bars 6 and 6a.

The back is formed by the metallic straps 7 whose lower ends are inserted between the two rear seat bars 6 and 6a in the spaces between the seat straps 5.

Each back strap has a ribbed plate 7a on its rear surface and through these ribs extends a tie bolt 8 the ends of which are extended through the arms 1b near the rear thereof.

Resiliency in the seat is secured by bending the front ends of the seat straps down, then rearwardly and then forwardly into a U-shape, the fastening to the front seat bar being made by bolts 5a passing through the ends of

2

the lower limbs of the U and through the front bar. Washers 5b are placed in the U-bends of the straps 5 to eliminate the springing or drawing of the strap portions in the U-bend together and thus facilitate the tightening of the bolts 5a.

In assembling the chair the end pieces are connected by the tie 2 and the front seat bar, and the seat straps for the entire seat unit are then bolted to the latter and their rear ends inserted and fastened between the rear bars 6 and 6a. The lower ends of the back straps are then inserted between the rear bars and the tie bolt 8 is then inserted through the ribs on the rear of the back straps.

At this stage the entire seat and back section is assembled, but due to the limited initial bend at the front of the seat straps the seat has its upper end above its intended final position (compare Figs. 3 and 4). The back of the seat is then forced down into its intended position by flexing the seat straps at their front ends. When in place the section is locked by passing the ends of the bolt 8 through the ends of the arms.

There is also provided means converting the above chair into a glider. These consist of two arched members 9 tied together by the ties 10 and 10a and located on the outside of the end pieces. On the horizontal part of each member is pivoted at 11a—11a two dependent hangers 11, one towards the front and the other towards the rear, the lower ends of which are pivoted to the base 1a at 11b. As the end pieces of the chair and the members 9 are in different vertical planes the two ends of these hangers are offset laterally from each other by the bent portion 11c (Figs. 2 and 6) thus causing a centering of the seat. By preference the rear hangers are shorter than those towards the front as thereby a swinging and a gliding sensation is produced. To strengthen the end pieces 1 against distortion braces 12 may extend from the arms at a point above the front bar to the base section.

Having thus described my invention, what I claim is:

A chair or settee structure comprising two U-shaped members, forming bases, legs and arms, a rod securing said members together in spaced relation, a front seat bar supported by said U-shaped members, a rear seat bar, one piece seat straps of pretensioned metal free of protuberances attached to said rear seat bar and having their front ends curved downwardly and inwardly resting upon and attached to said front seat bar, back straps having their lower ends securing to said rear seat bar, means engaging said back straps intermediate their ends and affixed to the arms of the U-shaped members, said back straps and said means serving to maintain said seat straps in a state of compression, and means for varying the height of the front ends of the seat straps.
